FASTENING INSERTING MACHINE

Augustus D. Willhauck, Stoneham, Mass., assignor to United Shoe Machinery Corporation, Flemington, N. J., a corporation of New Jersey

Application July 7, 1943, Serial No. 493,742

17 Claims. (Cl. 1—30)

1

This invention relates to machines for use in the manufacture of shoes and is illustrated as embodied in an improved fastening inserting machine which constitutes part of a heel-seat lasting machine of the general type disclosed in United States Letters Patent No. 2,214,741, granted September 17, 1940, on an application filed in the name of Fred N. La Chapelle.

As disclosed in the above-mentioned Letters Patent, shoe uppers, which have been shaped to the heel ends of lasts and have been inwiped over insoles secured to the bottoms of the lasts, are secured to the insoles by fastenings formed from strips of fiber fastening material and driven through the upper and the insole by tools which operate first as awls to form holes extending through the insole and the overwiped margin of the upper and then as drivers to drive the fastenings into the holes. In order that the shoe upper shall be effectively secured to the insole by fastenings such as referred to above, it is desirable that the lengths of the fastenings as well as the depths of the holes for receiving said fastenings shall be varied in accordance with variations in the combined thickness of the upper and the insole.

It is an object of the present invention to provide an improved heel-seat lasting machine of the type referred to above, by the use of which shoe uppers and insoles of different combined thicknesses may be quickly and effectively secured together.

With the foregoing object in view, the illustrative machine comprises, in combination with an actuating member movable in a fixed path and operatively connected to tools which are movable, together with wipers, lengthwise and laterally of a shoe being operated upon and are also movable first as awls and then as drivers relatively to the wipers, mechanism for varying the starting positions of the tools with relation to the actuating member in accordance with the desired limit of movement of the tools in one direction. In order that the tools shall operate effectively as awls to form holes extending through the combined thickness of the inturned margin of the upper and the insole of the shoe and then as drivers to drive fastenings into the holes, said mechanism for varying the starting positions of the tools is movable, in accordance with a feature of the present invention, in response to movement of means for shearing strips of fastening material to form the fastenings. The shearing means comprises an operating lever, hereinafter referred to as a shear lever, which remains in an

2

initial or primary rest position until the tools, which are of cylindrical form, have operated as awls, and is then moved to a secondary rest position in which it remains until the tools have operated as drivers.

The mechanism for varying the starting positions of the tools with relation to the actuating member, which is illustrated as a spring-pressed plunger and is twice released for movement in a fixed path under the action of a spring during each cycle of operation of the machine, comprises a crank, said crank being secured to the shear lever and having an elongated groove for receiving a slide collar pivotally mounted upon a coupling pin. The coupling pin, which may be pivotally connected to the crank in different positions lengthwise of the crank groove, is operatively connected to one end of a driving lever pivoted at its central portion to the plunger, the other end of the driving lever being connected through links to the tools.

When the shear lever is in its primary rest position, movement of the coupling pin into different adjusted positions lengthwise of the groove 25 of the crank causes the driving lever to rock into different positions upon the plunger, thus varying the positions of the tools with relation to the plunger. Since the plunger has a fixed path of travel, it will be apparent that the limit of 30 movement of the tools operating as awls in one direction varies in accordance with the setting of the coupling pin lengthwise of the crank groove, such setting being quickly effected by the operator when the machine is at rest through the provision of a calibrated scale and index line construction.

When the shear lever is in its secondary rest position, the groove of the crank, which, as above stated, is secured to the shear lever, is so arranged that irrespective of the adjustment of the coupling pin lengthwise of the crank groove the driving lever will remain in a constant position, hereinafter referred to as a neutral starting position, upon the plunger and accordingly 45 the tools will remain in the same starting positions.

In order to vary the distance which the tools travel below the work engaging faces of the wipers to penetrate the combined thickness of 50 the insole and the inturned margin of the upper, the coupling pin is moved into different adjusted positions along the groove of the crank, the arrangement being such that when the shear lever is in its primary rest position, in which it 55 remains while the machine is at rest and until

the tools have completed their operations as awls, the tools during their work penetrating strokes move a predetermined distance below the work engaging faces of the wipers. After the fastening receiving holes have been formed in the work, the shear lever moves to its secondary rest position, thus moving the tools to their neutral starting positions with relation to the plunger. Accordingly, when the shear lever is in its secondary rest position the tools are in their neutral starting positions irrespective of the starting positions of the tools at the beginning of their work penetrating strokes, the arrangement being such that during the strokes of the tools operating as drivers the ends of the tools move to but not substantially beyond the work engaging faces of the wipers, thus insuring that the fastenings are driven flush with the outer face of the inturned margin of the upper.

In order to supply strips of fiber fastening material to the machine, there are provided a pair of feed rolls which are operated during each cycle of operation of the machine by a one-way clutch of the Horton type. The amount of feed of the fiber fastening material per cycle of operation of the machine can be changed as desired by varying the throw of a lever which operates an outer driving sleeve of the clutch. To insure against any tendency of the strip of fiber fastening material to be fed backwards during the retractive movement of the driving sleeve of the above-mentioned clutch, there is provided another clutch which is similar in construction and arrangement to the first-named clutch but has an outer sleeve which is secured to the frame of the machine.

In trying out the wiping action of the machine, for example, it is desirable to render the tools inoperative and to stop the feed of the strips of fiber fastening material. Accordingly, the illustrative machine is provided with means comprising a single control member for retaining the tool operating plunger against movement and for stopping movement of the feed operating clutch.

The various features of the invention will be understood and appreciated from the following detailed description read in connection with the accompanying drawings, in which

Fig. 1 is a side view, partly broken away, of a machine in which the invention is embodied;

Figs. 2 and 3 are vertical sections on line II—II of Fig. 4, showing portions of the heel-seat lasting and fastening inserting mechanism of the machine during two stages of its operation;

Fig. 4 is a horizontal sectional view, partly broken away, the left and right halves of which are taken on lines IV—IV and IVa—IVa, respectively, of Fig. 2;

Fig. 5 shows in side elevation portions of the fastening inserting mechanism of the machine;

Fig. 6 is a section on line VI—VI of Fig. 5;

Figs. 7 and 8 are enlarged exploded and side views, respectively, illustrating in detail the fastening inserting mechanism;

Fig. 9 is a side view, partly in section, of mechanism for feeding the strips of fiber fastening material to the machine;

Fig. 10 is a section on line X—X of Fig. 9;

Fig. 11 is an exploded view of portions of mechanism for rendering the fastening inserting mechanism inoperative; and

Fig. 12 is an angular view of the heel-seat portion of a shoe which has been operated upon by the illustrative machine.

The machine herein illustrated is described

with reference to shaping shoe upper materials 20 (Figs. 2, 3, 4 and 12) about the heel end of a last 22, which is mounted upon a jack post 24 (Fig. 1) and to the bottom of which an insole 26 has been tacked, and to securing said materials, which are commonly referred to as an upper, to the insole by fiber fastenings 28 (Figs. 3 and 12). The shoe on the jack 24 is positioned with its heel-seat face 30 arranged slightly above the plane of the bottom faces 32 of wipers 34, the heel-seat face of the shoe being held by the jack in engagement with a rear work rest 36 (Figs. 2 and 4) and lateral work rests 38, and the rear end of the shoe being held in forced engagement with the rear end of a U-shaped heel band 42.

During the latter part of the shoe positioning operation, the heel band 40 is clamped around the counter portion of the shoe and co-operates with the jack 24 and the work rests 36, 38 in securing the shoe against movement. The work rests 36, 38 are initially engaged by the inturned margin 42 of the upper 20, as shown in Figs. 2 and 4, and during the lasting operation are moved inwardly by the wipers 34 into positions over the exposed insole 26 of the shoe and away from the then inwiped margin 42 of the upper, as shown in Fig. 3.

Since the machine as a whole, including the shoe positioning mechanism and mechanism for operating the wipers 34, is fully disclosed in the above-mentioned Letters Patent No. 2,214,741, only such parts of said mechanism as are deemed necessary to refer to in disclosing my invention will be hereinafter described.

The wipers 34 are secured by screws 44 (Figs. 2 and 4) and dowel pins 45 to wiper carriers 46 mounted upon a slide 48 which is movable forwardly and rearwardly along a rectilinear guide-way 50 (Fig. 4) of the machine frame 51. Each of the wiper carriers 46 is guided for arcuate movement on the slide 48 about a vertical axis 52 which, as will appear later, is coincident with the axis of a vertically movable fulcrum pin 54, by the provision of an arcuate tongue 56 fitting in a complementally shaped groove 58 formed in the slide 48, the carrier being confined on the slide by a cover plate 60 secured to the slide by screws 62. The slide 48 is moved lengthwise of a shoe positioned in the machine, to impart advancing and retractive movement to the wipers 34, by a cam path 64 (Fig. 1) which is secured to a main drive shaft 65 and is engaged by a roll 66 carried by a rearward extension of the slide. The wipers 34 are swung toward each other during and in time relation with their advancing movement with the slide through the provision of links 68 (Fig. 4) which are pivoted at their forward ends to corresponding wiper carriers 46 and at their rear ends to mechanism operatively connected to a roll 70 (Fig. 1) engaging with a cam path 72 secured to the drive shaft 65.

The fiber fastenings 28 which, as will appear later, are formed from strips 74 of fiber fastening material, after being delivered to vertical passages 76 (Figs. 2, 3 and 4) formed in upstanding arcuate flanges 78 of the wipers 34, are driven by gangs of vertically movable tools 80 into holes 82 (Figs. 3 and 12) previously formed in the upper 20 and the insole 26 by said tools operating as awls.

Secured by screws 84 (Figs. 2 and 4) and the dowel pins 45 to each of the wiper carriers 46 is a tool guiding block 86 and an upstanding bracket 88, the brackets being secured by screws 90 and

dowel pins 92 to corresponding blocks 94 forward central portions 96 of which overlap and are provided with bores alined to receive the fulcrum pin 54. As above stated, the tongues 56 of the wiper carriers 46 and the grooves 58 of the slide 48 are centered about the axis 52 of the fulcrum pin 54. Each of the blocks 94 is provided with an arcuate slot 98, through which flexible conduit tubes 100 for receiving the strips 74 of fiber fastening material pass, and a bore 102 for receiving a shank of a tool carrier or driver bar 104 having secured to its lower end the tools 80 which are arranged in an arcuate row.

The driver bars 104 are mounted for vertical sliding movement in the bores 102 of the blocks 94, through the provision of mechanism hereinafter described, and are held by keys 106 against turning in the blocks. As above explained, after the tools 80 have operated as awls to form the holes 82 in the upper 20 and the insole 26, they are again operated as drivers to drive the fastenings 28 into the holes. The tools may therefore be referred to as drivers.

The upper ends of the tools 80 at each side of the machine fit in recesses 108 (Fig. 2) formed in an arcuate strip 110 which is T-shaped in cross section and together with an arcuate assembling strip 111 pinned or otherwise secured to the strip 110 fits in a complementary slot 112 formed in the lower end of the associated driver bar 104. The strips 110 and 111 are secured against movement in the slot 112, with the drivers 80 arranged in driver passages 113 of the tool guiding block 86, by a spring-pressed retaining pin 115 which fits in a bore 118 of the driver bar 104 and extends into a recess 120 of the strip 111. It will thus be apparent that one or more drivers may be removed from either of the strips 110, preparatory to replacing said drivers, after lifting a stud 122, which is secured to the pin 116 and extends into a recess 124 of the driver bar 104, and sliding the strip out of the slot 112.

Each of the driver bars 104 has at its upper end a circumferential groove 126 for receiving bifurcations 128 of a link 130 pivoted through a link 132 to the forward end of a tool operating lever 134, which may also be referred to as a driving lever. The rear end of the tool operating lever 134 is operatively connected to a shear lever 136 through mechanism which will be described in detail and comprises a link 140. A pin 142 carried by the lower end of the link 140 serves as a fulcrum about which the driving lever 134 is rocked, by a spring-pressed plunger 144 to which it is pivoted, to operate the tools 80.

Each of the upstanding brackets 88 is provided with an arcuate row of passages 146 for receiving lower end portions of the flexible conduits 100, such passages being in registration with passages 148 formed in the associated tool guiding block 86. Slidably mounted in guideways 150 formed between associated tool guiding blocks 86 and wiper carriers 46 are loader or shear blocks 152 each having an arcuate row of passages 154. Each of the loader blocks 152 is provided with vertical guideways 156 for receiving blocks 158 pivoted upon a pin 159 which is carried by the lower end of a bell-crank lever 160 mounted upon a fulcrum pin 162 secured to the associated bracket 88. A block 164 pivoted upon a pin 165 carried by a bifurcated rear end portion of each of the bell-crank levers 160 fits in a guideway 166 of a forked arm 168 at the lower end of a vertical plunger 170 which is mounted for slid-

ing movement in a bore 172 of the associated bracket 88.

When the plungers 170 are depressed, through mechanism which will be described later, they impart through the bell-crank levers 160 forward sliding movement to the loader blocks 152, causing the strips 74 of fiber fastening material, which have previously been fed a predetermined distance into the passages 154 of said blocks, to be sheared, thereby forming the fastenings 28. Forward movement of the loader blocks 152 is continued until the passages 154 are in alinement with the passages 114 in the tool guiding block 86 and the passages 76 in the wipers 34, as shown in Fig. 3, at which time the loader blocks come to rest, the fastenings 28 being ready for delivery to the passages 76 so that they may be later operated upon by the tools 80 operating as drivers.

Interposed between a washer 174 on the bracket 88 and a nut 176 threaded onto the upper end of the plunger 170 is a spring 178 which, when the machine is at rest, as illustrated in Fig. 2, retains the corresponding loader block 152 in engagement with a surface 180 of the wiper carrier 46, the passages 154 of the loader block 152 at this time being in alinement with the passages 148 of the tool guiding block 86 for receiving the strip 74 of fiber fastening material. In order to insure against movement of the nut 176 upon the plunger 170, there is provided a lock nut 122, the nut and the lock nut being so positioned that when a rod 184, which will be hereinafter described and operates the plungers 170, is at the bottom of its stroke, the passages 154 in the loader block 152 are in registration with the passages 76, 114 of an associated wiper 34 and tool guiding block 86, respectively.

The plungers 170 are operated at a predetermined time in the cycle of operation of the machine against the action of the springs 178 by the rods 184 which are mounted for vertical movement in bearings 186 of the machine frame and are pivoted to links 188. The upper ends of the links 188 are pivoted to arms 190, respectively, of the shear lever 136 which is secured to a shaft 192 fulcrumed in the machine frame and is pivoted at its rear end, through a link 194 (Figs. 1 and 8), to a slide 196 vertically movable in a guideway 198 of the machine frame. The slide 196 carries a roll 200 engaging a path cam 202 secured to the rear end of the shaft 65, the shape of the path cam being such that after the tools 80 have been reciprocated to form the fastening receiving holes 82 in the upper 20 and the insole 26 the shear lever 136 is swung in a clockwise direction from a primary rest position, shown in full lines (Fig. 8), to a secondary rest position 136a, shown in dash lines, to impart downward movement to the rods 184.

It will thus be understood, and as fully disclosed in the above-mentioned Letters Patent No. 2,214,741, that prior to depressing the rods 184 each of the plungers 170 has moved, together with its associated upstanding bracket 88, in response to the advancing and closing movement of the wipers 34. Accordingly, the operative positions of the plungers 170 vary to a slight extent in accordance with the closed positions of the wipers 34 and in order to insure that the plungers shall be engaged by the rods 184 irrespective of the closed setting of the wipers 34, the lower end of each of the rods 184 is enlarged to a considerable extent.

The mechanism for operating the driving lever

134 to cause the tools 80 to operate first as awls and then as drivers will now be described. As above stated, the lever 134 is pivoted at its central portion to the plunger 144 which is vertically slideable in guideways 206 (Figs. 5, 6 and 8) of the machine frame and the lower end of which carries a roll 208 and a bearing plate 209. The roll 208 is forced against a cam 210, which is secured to the drive shaft 65 and has commonly centered cylindrical faces 211, 213 and lifting faces 215, 217, by a coil spring 212. The spring 212 is housed in a recess 214 formed in the upper end of the plunger 144 and has its upper end in engagement with a thimble 216 (Fig. 1) threaded into a bracket 218 secured by screws 220 to the machine frame.

The cam 210 is rotated in a counterclockwise direction, as viewed in Figs. 6 and 7, and when edges 222, 224 of the same pass the bearing plate 209 the plunger 144 is released and by reason of pressure of the spring 212 against it causes the lever 134 to swing downwardly about its fulcrum pin 142, thereby operating the tools 80.

Downward movement of the plunger 144 is limited by a fiber stop 226 (Figs. 1, 5 and 7) which is secured to the machine frame and is engaged by a nut 228 threaded onto the plunger. The nut 228 is initially adjusted on the plunger 144 in accordance with the desired limit of downward movement of the plunger and is maintained in its adjusted position by a lock nut 230. The stop 226 is so located that with the link 140 in a neutral position, shown in dash lines 140a Fig. 8, which position will be referred to later and is the position assumed by the link just prior to and during the time that the tools 80 are operating as drivers, the tools, during downward movement of the plunger 144, move downward until their lower ends are moved into alignment with or, as usually preferred, just below the bottom or work engaging faces 32 of the wipers 34. As will be explained presently, since the plunger 144 has a constant stroke, the link 140 is in a raised full-line position when the tools 80 operate as awls, in order that the starting positions of the tools shall be lower than they are when the link is in its neutral position 140a, thereby insuring that during the fixed downward stroke of the plunger 144 the lower ends of the tools move a predetermined distance below the bottom faces 32 of the wipers 34, such distance being approximately equal to the combined thickness of the upper 20 and the insole 26 of the shoe.

There will now be described mechanism for quickly and effectively varying, at the will of the operator, the limit of downward movement of the tools 80 operating as awls and for maintaining constant the limit of downward movement of the tools operating as drivers. The limit of downward movement of the tools 80 operated as awls may be varied by moving a slide 232 (Figs. 1, 5 and 7) into different adjusted positions upon a stroke controlling lever 234, as will appear later, to change the position of the link 140 and therefore the angular starting position of the driving lever 134 upon the plunger 144. Mechanism operatively connecting the stroke controlling lever 234 and the link 140 is so constructed and arranged that when the shear lever 136 has been rotated in a clockwise direction to its dash-line position 136a (Fig. 8) to form the fastenings 28 and to move the loader block 152 into a position in which its passages 154 are in alignment with passages 76, 114 of the wiper 34 and the tool guiding block 86, respectively, the link 140 is

always in its neutral dash-line position 140a so that irrespective of the setting of the slide 232 upon the stroke controlling lever 234 the driving lever 134 is always in the same angular starting position, shown in dash lines 134a (Fig. 8), upon the plunger 144.

As best illustrated in Fig. 7, the upper end of the link 140 is pivoted to a bell-crank lever 236 mounted for rocking movement upon the shaft 192 to which, as above stated, the shear lever 136 is secured. Pivoted to a depending arm of the bell-crank lever 236 is a link 238 having pivoted to its rear end an arm 240 secured by a setscrew 242 to a shaft 244. Also secured to the shaft 244 is a sleeve 246, the sleeve together with the shaft being mounted for rocking movement in bearings of the machine frame. In order that the shear lever 136 may be rocked without engaging the shaft 244 and the sleeve 246, it is provided with enlarged holes 248, 250.

Formed integral with the sleeve is a crank 252 provided with a groove 254 in which fits a block 256 pivoted upon a fulcrum pin 258 secured by a nut 260 to the rear end of the stroke controlling lever 234. Threaded into the frame of the machine is a bearing pin 262 upon which the stroke controlling lever 234 is pivotally mounted. Secured to and slidably adjustable upon the stroke controlling lever 234 is the slide 232 which is movable forwardly and rearwardly in a guideway 264 formed by the lever 234 and a cover 266 which is secured to the side of the lever by a screw 268. The cover 266 is provided with a bearing hole 270 for a pin 272 which has secured to it a pinion 274 meshing with a rack 276 of the slide 232, the outer end of the pin being of hexagonal shape to facilitate rotating the pin and thus moving the slide 232 to a desired adjusted position lengthwise of the guideway 264 for purposes which will appear presently. The slide 232 has a bore 278 for receiving a stud of a coupling pin 280 which has pinned to it a flat-sided collar 282 shaped and arranged for movement in an elongated slot 284 at the inner face of the stroke controlling lever 234.

Formed integral with the shaft 192 to which the shear lever 136 is secured is a crank 286 having an elongated rectilinear groove 288 in which fits a slide block 290 pivoted upon an inner portion of the coupling pin 280, said inner portion of the coupling pin being short enough to insure that the collar 282 shall engage an opposite face of the crank 286. Threaded onto the outer end of the coupling pin 280 is a nut 292 by the provision of which the collar 282 on the pin may be clamped against the slide 232 in order to secure the slide in its adjusted position upon the stroke controlling lever 234. As will appear later, when the machine is at rest and during the time that the tools are operative as awls, the shear lever 136 is in its raised position, shown in full lines Fig. 8, the lengthwise median plane 294 of the rectilinear slot 288 of the crank 286 extending upwardly and forwardly at a slight angle α to the horizontal.

In order quickly and effectively to position the slide 232 in different adjusted positions upon the stroke controlling lever 234 and accordingly the coupling pin 288 in different adjusted positions lengthwise of the groove 288 of the crank 286, the slide is provided with an index line 296 which may be arranged opposite any one of a number of graduations of a calibrated scale 298 on the lever. When the index line 296 on the slide 232 is arranged in alignment with the "0" on the

scale 298, the axis of the coupling pin 280 is coincident with the axis of the shaft 192.

During the downward strokes of the tools 80 operating as drivers, the shear lever 136 is in its dash-line position 136a, the central lengthwise plane 294 of the crank groove 288 at such time being arranged in a horizontal position 294a and passing through the axis of the bearing pin 262 about which the stroke controlling lever 234 is rocked. It will thus be apparent that when the index line 296 of the slide 232 is set at "0" and the plunger 144 is in its raised position, the driver operating lever 134 will assume its dash-line position 136a on the plunger 144 irrespective of whether the shear lever 136 is in its raised full-line position or its dash-line position 136a. With such an adjustment the link 109 and the driving lever 134 are always in what may be described as neutral positions 136a, 134a, respectively. Accordingly, the lower ends of the tools during their work penetrating and fastening driving strokes move to but not substantially beyond the bottom faces of the wipers 34.

When it is desirable for the tools 80 during their downward movement as awls to move $\frac{1}{16}$ of an inch, for example, below the bottom faces 32 of the wipers 34 in order to penetrate the maximum combined thickness of the insole 26 and the overwiped upper 20, the nut 292 is loosened and the pin 272 is rotated in a counterclockwise direction, as viewed in Fig. 7, until the index line 296 of the slide 232 is arranged opposite the "7" on the scale 298 of the stroke controlling lever 234.

When the machine is adjusted for maximum penetration as above described, mechanism hereinafter described, for feeding the strips 74 of fiber fastening material is correspondingly adjusted to produce fastenings 28 of maximum length.

In moving the slide 232 from "0" to "7" upon the stroke controlling lever 234, the coupling pin 280 is moved upwardly and forwardly along the groove 288 from a position in axial alinement with the shaft 192 into the position indicated by full lines in Fig. 8. Such adjustment causes the stroke controlling lever 234 and the crank 252 to rotate in counterclockwise directions from their horizontal dash-line positions 234a, 252a (Fig. 8) to their full-line positions and, through the above-described mechanism, the driving lever 134 to move from its dash-line position 136a to its full-line position, thereby lowering the tools $\frac{1}{16}$ of an inch, the lower ends of the tools moving from the position indicated by reference numeral 300 to the position indicated by reference numeral 302.

It will be understood that the work, prior to being operated upon by the tools, has been clamped in the machine through the provision of the above-described mechanism and that the strips 74 of fiber fastening material have been fed downwardly $\frac{1}{16}$ of an inch into corresponding passages 154 of the loader block 152 by mechanism hereinafter described. After the wipers 34 have been advanced and closed to wipe the margins of the upper 20 inwardly over the insole 26, the plunger 144 is released as the edge 222 of the cam 210 passes the bearing plate 208 of the plunger, thus enabling the plunger to be moved downwardly under the action of the spring 212 until arrested by the stop 226. Downward movement of the plunger 144 causes the driving lever 134 to be moved from its full-line position shown in Fig. 8 to its dotted-line position 134b, with

the result that the lower ends of the tools operating as awls move $\frac{1}{16}$ of an inch below the bottom faces 32 of the wipers 34 to the level indicated by reference numeral 301, thereby forming the fastening receiving holes 82 in the work, the tools moving into approximate engagement with a heel plate 304 (Figs. 2, 3 and 12) of the last 22. The plunger 144 is then raised by engagement of the surface 215 of the cam 210 with the roll 208 of the plunger 144 to return the driving lever 134 to its full-line position shown in Fig. 8.

After the tools 80 have been raised out of the loader block guideways 150, the shear lever 136 is rocked from its full-line position (Fig. 8) to its dash-line position 136a, causing the rods 184 to depress the plungers 178 and through the crank levers 160 to move the loader blocks 152 inwardly, that is, to the right, as shown in Figs. 2 and 3, to shear the portions of the strips 74 of fiber fastening material extending into the passages 154 of the loader blocks and to transfer such passages and the fastenings 28 housed therein into registration with corresponding passages 76, 114 of the wipers 34 and the tool guiding blocks 86, respectively. Movement of the shear lever 136 to its dash-line position 136a causes the central lengthwise plane 294 of the groove 288 of the crank 286 to move from its inclined position to its horizontal position 294a, thus rocking the stroke controlling lever 234 in a clockwise direction about its fixed bearing pin 262 back to its horizontal position 234a and, through the mechanism above described, rocking the driving lever 134 from its full-line position to its dash-line position 134b, the latter position being the same position which the driving lever assumes when the slide 232 is set at "0."

When the edge 224 of the cam 210 has passed the bearing plate 208 of the plunger 144, the plunger is again depressed by the spring 212 until its nut 228 engages the stop 226, thus moving the driving lever 134 from its dash line position 134a to its dash-dot position 134c, shown in Fig. 8, and lowering the tools 80, operating as drivers, until their lower ends are moved to or preferably just below the bottom faces 32 of the wipers 34 so as to drive the fastenings 28 into the previously formed holes 82. The plunger 144 is then raised by engagement of the surface 217 of the cam 210 with the roll 208 of the plunger, the driving lever 134 being moved back to its dash-line position 134a. The shear lever 136 is thereafter rocked in a counterclockwise direction, as viewed in Fig. 8, back to its raised full-line position, causing the crank 286 to be moved back to its inclined full-line position and the driving lever 134 to be moved from its dash-line position 134a to its full-line position ready for the next cycle of operation of the machine.

In checking the action of the wipers 34, for example, it is desirable to run the machine without driving the fastenings 28. Accordingly, there is provided a lock pin 306 (Figs. 6 and 11) which is mounted for sliding movement in a bore 308 of the machine frame 51 and may be released to enter a recess 310 (Fig. 6) in the plunger 144 for the purpose of retaining said plunger in its raised position. A reduced shank 312 of the lock pin 306 extends through a bore 314 of a pin support 316 secured by a setscrew 318 to the frame of the machine. The lock pin 306 is constantly urged to the right as viewed in Figs. 6 and 11 by a spring 320 interposed between the support 316 and a shoulder of the lock pin, and mounted on the rear end of the reduced shank 312 of the

pin is a hand knob 322 provided with deep and shallow slots 324, 326 which may be selectively brought into registration with a lug 328 on the fixed pin support 316. When the deep slot 324 of the hand knob 322 is in registration with the lug 328 of the support 316, the pin 306 extends into the recess 310 of the plunger 144 and holds the same in its raised idle position. When the shallow slot 326 of the hand knob 322 is in registration with the lug 328 of the pin support 316, the pin 308 is in its withdrawn inoperative position, shown in Fig. 6, and has no effect on the movement of the plunger 144.

The strips 74 of fiber fastening material are fed a predetermined distance into the passages 154 of the loader blocks 152 during the first part of each cycle of operation of the machine, by a pair of feed rolls 330, 332, the roll 330 being secured to a shaft 334 which is mounted for rotation in a bracket 336 secured by screws 338 to the frame 15 of the machine and which has secured to its left end, as viewed from the front of the machine, a driven inner sleeve 340 of a one-way clutch 346 of the Horton type. The roll 330 is preferably made of steel and is provided with circumferential grooves 348 in which the respective strips 74 of fiber fastening material are pressed by the roll 332, which is made of rubber or other yieldable material and is secured to a shaft 350 rotatable in a carrier 352 hinged at its lower end to the bracket 336. The rubber roll 332 is driven at approximately the same peripheral speed as the steel roll by the provision of intermeshing gears 351, 353 (Fig. 9) which are secured to the shafts 334 and 350, respectively.

The strips 74 of fiber fastening material are supplied from arcuate guides 354 (Fig. 1) from reels (not shown) and extend downwardly between the rolls 330, 332 (Figs. 9 and 10) and into the conduit tubes 108 (Fig. 2) through which they are fed into the passages 154 of the loader blocks 152.

The roll carrier 352 is held in its operative position, shown in Fig. 9, by a thumb nut 356 threaded onto a coupling pin 358 which is hinged at its rear end to the upper end of the bracket 336 and is normally arranged in a slot 360 formed in the upper end of the carrier. The thumb nut 356 is forced against a face 362 of the carrier with the desired amount of pressure necessary to cause the rubber roll 332 to force the strips 74 of fiber fastening material into the circumferential grooves 348 of the rigid roll 330. The rubber roll 332 may be readily swung away from the roll 330, preparatory to supply new strips 74 of fiber fastening material to the machine, for example, by backing away the thumb nut 356 and, after raising the pin 358, swinging the carrier 352 to its dropped position, shown in dash lines Fig. 9.

The roll 330 is fed step by step by the Horton clutch 346, which is of well-known construction and need not be described in detail herein. Formed integral with a driving outer sleeve 364 of the Horton clutch 346 is an arm 366 pivoted to a connecting rod 368 the rear end of which is mounted upon a collar 370 (Fig. 10) carried by a threaded coupling pin 372. The head of the coupling pin 372 is arranged in an upstanding arcuate groove 374 of T-shaped cross section formed in a lever 376 secured by a pin 378 to a shaft 380 which is mounted in a bracket 382 of the machine frame and to which a crank arm 384 is secured.

In order to insure against any back feed of

the rolls 330, 332, there is provided another one-way clutch 385 of the Horton type an inner sleeve 387 of which is secured to the shaft 334 and during the retractive movement of the arm 366 is locked to an outer sleeve 389 secured to the bracket 336.

The coupling pin 372 may be secured in different positions along the arcuate groove 374 of the lever 376 by the provision of a binding nut 386 which is threaded onto the coupling pin 372 and is arranged to force the collar 370 against the lever 376 and thus to pull the head of the pin against undercut faces of the groove 374.

The crank arm 384 is pivoted to a rod 388 the rear end of which is threaded into a yoke 390 (Fig. 1) having a bore 392 for receiving a rod 394 pivoted at its rear end to a bell-crank lever 396 mounted upon a fulcrum pin 398 supported upon an upstanding bracket of the machine frame 51. Threaded onto the forward end of the rod 394 is a nut 400 and interposed between a collar 402 pinned to the rod and the rear end of the yoke 390 is a spring 404 serving normally to hold the nut 400 against a face 406 of the yoke 390. The bell-crank lever 396 is operatively connected through a link 408 to a slide 410 movable in a vertical guideway 412 of the machine frame and carrying a roll 414 engaging a path cam 416.

The amount of feed of the strips 74 of fiber fastening material into the passages 154 of the loader blocks 152 during each cycle of operation of the machine varies in accordance with the degree of rotation of the shafts 334, 350 by the crank arm 366 of the one-way clutch 346.

When the axis of the coupling pin 372 is coincident with the axis of the shaft 380 upon which the lever 376 is mounted, no rocking motion is imparted to the crank arm 366 upon rocking movement of the lever 376. The amount of throw of the crank arm 366 is dependent upon the position of the coupling pin 372 lengthwise of the groove 374 of the lever 376, the farther the pin is located from the axis of the shaft 380 the greater being the feed of the strips 74 into the passage 154 of the loader blocks 152 during the constant arcuate swinging movement of the lever 376.

In order that the operator may quickly and effectively set the coupling pin 372 in different positions upon the lever 376 for different desired feeds, the connecting rod 368 has secured to its rear end a pointer 418 which overlies a calibrated scale 420 secured to the lever 376, the numbers representing 16ths of an inch of feed, it being noted that the maximum feed is $\frac{1}{16}$ of an inch, such feed, as above described, being equal to the maximum penetration of the work by the tools 80 operating as awls.

When the tools 80 are rendered inoperative by reason of the lock pin 306 extending into the recess 310 of the plunger 144, it is desirable that the feeding of the strips 74 of fiber fastening material shall cease. Accordingly, there is provided mechanism for locking the lever 376 against movement when the plunger 144 is rendered inoperative, such mechanism comprising a collar 422 (Figs. 1, 5 and 6) which is mounted for rocking movement upon the pin support 316 and is operatively connected through a link 424 to an arm 426 (Figs. 9 and 10) secured by a split collar-and-screw construction 428 to one end of a shaft 430 journaled in the machine bracket 382. Secured to the other end of the shaft 430 is a stop 432 which, when the arm

426 is swung in a counterclockwise direction, as viewed in Fig. 9, swings to a dash-line position beneath a shoulder 434 of a lug 436 formed integral with the crank arm 324 (Fig. 10).

The collar 422 has secured to it a rod 438 (Figs. 6 and 11) which is arranged in a notch 440 of the hand knob 322, the arrangement being such that when the knob is pulled and rotated, causing the deep slot 324 to register with the lug 328 of the pin support 316 and thereby rendering the plunger 144 inoperative, the collar 422 is rotated on the support 316 and through the mechanism above described causes the stop 432 to swing beneath the lug 436, thus rendering the fiber fastening feeding mechanism inoperative. When the lug 436 is locked against movement by the stop 432, the rod 394 (Fig. 1) during its forward travel compresses the spring 404, the rod sliding idly in the bore 392 of the yoke 390.

The operation of the machine, briefly summarized, is as follows. The operator mounts the shoe upon the jack post 24, swings said post rearwardly to carry the heel end of the shoe into the heel band 40, and raises the post to force the heel-seat face of the shoe against the work rests 36, 38. With the shoe thus positioned, the operator starts the machine, whereupon the jack 24 is swung farther rearwardly to press the shoe more firmly against the heel band 40, the heel band is closed about the heel end of the shoe, and the heel rests 36, 38 are moved downwardly to a slight extent to cause the heel band to wipe the shoe upper upwardly toward the edge of the heel seat. During this time the feed rolls 330, 332 are rotated in directions to feed suitable lengths of strips 74 of fastening material downwardly into the passages 154 of the loader blocks 152. The heel band 40 is then further closed yieldingly against the sides of the shoe and the jack upon which the shoe is mounted is forced still more firmly against the heel band, and the shoe is pressed more firmly against the work rests 36, 38 through the jack post, after which the wipers 34 are advanced and closed to wipe the margin of the upper materials inwardly over the sole. As the wipers 34 complete their advancing and closing movements, the tool operating lever 134 is released and under the action of the spring 212 operates the tools 80 acting as awls to form in the overwiped margin of the upper and in the sole, fastening receiving holes in alignment with the passages 76 in the wipers, after which the lever 134 is raised to move the tools 80 to their raised retracted positions.

The shear lever 136 is then swung clockwise, as viewed in Figs. 1, 5 and 8, to its lowered position, causing the loader block 152 to be moved relatively to the wipers 34 to sever the portions of the strips 74 of fastening material fed into the passages 154 and to move said passages into alignment with the tools 80 and the openings 76 in the wipers 34.

Thereafter, the driver operating lever 134 is again released and under the action of the spring 212 operates the tools 80 which act as drivers to insert the fastenings into the fastening receiving holes formed in the margin of the upper and in the sole, after which the shear lever 136 and the tools are moved to their raised retracted positions, the shoe is released from pressure of the jack post and the heel band 40, and the work rests 36, 38 and the wipers are moved back to their idle starting positions.

Having described my invention, what I claim as

new and desire to secure by Letters Patent of the United States is:

1. In a fastening inserting machine, a movable tool operative alternately as an awl and as a driver, means for operating the tool, means for shearing a strip of fastening material to form a fastening and for moving said fastening to a position to be operated upon, and mechanism movable in timed relation with said shearing means for causing the tool when operating as a driver to start at a constant predetermined position and for causing the tool when operating as an awl to start at a position different from said predetermined position.
  2. In a fastening inserting machine, a movable tool operative alternately as an awl and as a driver, means for operating the tool, means for shearing a strip of fastening material to form a fastening, mechanism movable in response to movement of said shearing means for causing the tool when operating as a driver to start at a constant predetermined position and for causing the tool when operating as an awl to start at a position different from said predetermined position, and means controlled by the operator for initially varying the starting positions of the tool when operating as a driver in accordance with different thicknesses of material to be penetrated by the tool when acting as an awl.
  3. In a fastening inserting machine, a reciprocating tool operative alternately as an awl and as a driver and having a stroke of a constant length, fastening forming means comprising a member movable from one position to another, and mechanism which is operatively connected to the tool and to said member and is constructed and arranged when said member is in one position to vary the starting position of the tool about to operate as an awl in accordance with the depth to which a work piece is to be penetrated by the tool, said mechanism also being so constructed and arranged that when said member is moved to another position the tool is moved to another starting position which is constant irrespective of any variations in the starting positions of the tool when acting as an awl.
  4. In a fastening inserting machine, a reciprocable tool operative alternately as an awl and as a driver and having a stroke of a constant length, means for shearing a strip of fastening material to form a fastening, said means comprising a member movable from a primary to a secondary position, and mechanism which is operatively connected to the tool and to said member and is constructed and arranged when said member is in said primary position to vary the starting position of the tool in accordance with the desired depth to which a work piece is to be penetrated by the tool operating as an awl, said mechanism also being so constructed and arranged that when said member is moved to said secondary position the tool is moved to the same predetermined starting position irrespective of the setting of the tool at the start of its work penetrating stroke.
  5. In a fastening inserting machine, means, comprising a member which is movable from a primary to a secondary position, for shearing strips of fastening material to form fastenings, a gang of movable tools which have constant strokes and operate alternately as awls and as drivers, and mechanism for operatively connecting said means to the tools for changing when said member is in its primary position the starting positions of the tools in order to vary
- 75 the limits of movement of the tools in one direc-

tion in accordance with the thickness of a work piece to be penetrated by the tools operating as awls, said mechanism being so constructed and arranged that when said member is moved from its primary to its secondary position it moves the tools to constant positions so that said tools in subsequently moving in said one direction to drive the fastenings will be arrested when their work engaging faces are substantially flush with an outside face of the work piece.

6. In a fastening inserting machine, a tool operative alternately as an awl and as a driver, a block constructed and arranged to form a fastening from a strip of fastening material and to deliver it into a position to be operated upon by the tool, a movable member, said block being movable in response to movement of said member, a plunger, a stop, a lever pivoted to the plunger, connections between the tool and the lever, resilient means for reciprocating said plunger until its movement is limited by said stop, and means responsive to movement of said member for varying the angular position of the lever on the plunger.

7. In a fastening inserting machine, a gang of reciprocable tools operating alternately as awls and as drivers and having strokes of a constant length, fastening forming means comprising a member movable from a primary to a secondary position, and mechanism which is operatively connected to the tools and to said member and is constructed and arranged when said member is in said primary position to vary the starting positions of the tools about to operate as awls in accordance with the depth to which a work piece is to be penetrated by said tools, said mechanism also being so constructed and arranged that when said member is moved to said secondary position the tools are moved to starting positions which are constant irrespective of any variations in the starting positions of the tools about to operate as awls.

8. In a fastening inserting machine, a reciprocating tool operative alternately as an awl and as a driver, a member which is mounted for reciprocation and is operated in one direction by a spring, a lever pivoted at its central portion to said member, operative connections between one end of the lever and the tool, means connected to the other end of the lever for initially moving it to a predetermined position upon the member, and a cam for releasing said member to enable the spring to operate the member in said one direction thereby to move the tool as an awl in one direction to form a hole in a work piece, said means also being constructed and arranged to rock the lever to another predetermined position upon said member after the hole has been formed preparatory to moving the tool as a driver in said one direction to insert a fastening into the hole.

9. In a fastening inserting machine, a tool operative alternately as an awl and as a driver, a plunger, a spring, a stop, a cam for forcing the plunger into a cocked position against the action of the spring and for releasing the plunger to enable it to be moved under the action of the spring until it is arrested by the stop, a driving lever pivoted to the plunger, means for operatively connecting one end of the driving lever to the tool, a block constructed and arranged to shear a strip of fastening material to form a fastening and to deliver said fastening into a position to be operated upon by said tool, a shear lever movable to effect movement of said block,

and adjustable connections between the shear lever and the other end of the driving lever.

10. In a fastening inserting machine, means, comprising a movable member, for severing a strip of fastening material to form a fastening, a tool, mechanism for reciprocating said tool to cause it to operate first as an awl for forming a hole in a work piece and then as a driver for driving said fastening into the hole, and calibrated connections responsive to movement of said member for causing the limit of reciprocation of the tool in one direction during its hole forming stroke to be more advanced than its limit of movement in said one direction during its driving stroke, said connections being initially adjustable with relation to said member to vary the limit of the tool when operating as an awl in said direction in accordance with the thickness to which the work piece is to be penetrated by said tool.

11. In a fastening inserting machine, a tool constructed and arranged to operate alternately as an awl and as a driver, a shear block constructed and arranged first to sever a strip of fastening material to form a fastening and then to transfer said fastening into a position in which it may be driven into a work piece by the tool, a driving lever operatively connected to the tool, a shear lever operatively connected to said block, a plunger to which the driving lever is pivoted, means for reciprocating the plunger in a fixed path, and mechanism operatively connected to the shear lever for moving the driving lever into different angular positions upon the plunger in accordance with the desired limit of movement in one direction of the tool operating as an awl, said mechanism being so constructed and arranged that when the fastening has been transferred into the position in which it can be operated upon by the tool the driving lever is restored to a predetermined constant neutral position upon the plunger irrespective of its prior position on the plunger.

12. In a fastening inserting machine, a gang of tools operative alternately as awls and as drivers, shear blocks constructed and arranged to sever strips of fastening material to form fastenings, mechanism, comprising a shear lever, for moving the blocks from positions in which they receive said fastening material to positions in which they have transferred the fastenings into positions to be driven into a work piece by the tools, a stop, a plunger, a lever which is pivoted to the plunger and is operatively connected to the tools, a cam operative against the plunger and constructed and arranged to release said plunger at predetermined times, a spring arranged to force the plunger against the stop upon release of the plunger by the cam, and mechanism operatively connecting the shear lever and the tool operating lever for initially rocking the tool operating lever into predetermined angular positions upon the plunger in accordance with the desired limit of movement in one direction of the tools operating as awls, said mechanism being so constructed and arranged that, when the shear lever is moved to transfer said fastenings into positions in which they are operated upon by the driver, the tool operating lever is moved to a different but constant position on the plunger so that during a subsequent stroke of the plunger the tool will drive the fastenings into the work piece flush with the outer surface of the work piece.

13. In a fastening inserting machine, a gang of tools operative alternately as awls and as drivers,

a pair of shear blocks each having passages, mechanism, comprising a shear lever which is mounted for rocking movement about a fixed axis from a primary position to a secondary position, for forming fastenings from strips of fiber fastening material extending into the passages of the shear blocks and for transferring said fastenings into positions in which they are driven into a work piece by the tools, a crank movable with the shear lever and having an elongated straight groove a central lengthwise plane of which passes through the axis about which the shear lever is rocked, a stroke controlling lever mounted for rocking movement about a fixed axis and carrying a coupling fitting in said groove of the crank, a plunger having a constant throw, mechanism comprising a driving lever which is pivoted to the plunger and is operatively connected to the tool, connections between the stroke controlling lever and the driving lever, means for securing the coupling in different adjusted positions lengthwise of the groove of said crank, said crank being so constructed and arranged that the central lengthwise plane of its groove extends to one side of the fixed axis about which the stroke controlling lever is rocked when the shear lever is in its primary position but is coincident with said axis when the shear lever is in its secondary position, thus insuring that irrespective of the position of the coupling lengthwise of the groove of the crank the stroke controlling lever will be moved back to the same constant position upon the plunger when the shear lever is in its secondary position, and means for operating the plunger.

14. In a fastening inserting machine, a tool operative alternately as an awl and as a driver, a member movable in an actuating fixed path, and mechanism operatively connecting said member and the tool, said mechanism comprising an element which is carried by said member and is movable into different adjusted starting positions upon said member to vary the limit of movement of the tool in one direction in accordance with whether the tool is to operate as an awl or as a driver.

15. In a fastening inserting machine, a tool

operative alternately as an awl and as a driver, a stop, means comprising an actuating member movable a constant distance determined by the stop, and a lever which is operatively connected to the tool and is bodily movable with and is initially adjustable upon said member in accordance with the desired limit of movement of the tool.

16. In a fastening inserting machine, means, comprising a movable member, for severing a strip of fastening material to provide a fastening, a tool, mechanism for reciprocating the tool to cause it to operate alternately as an awl to form a hole in a work piece and as a driver to drive said fastening into the hole, and means responsive to movement of said member for causing the limit of reciprocation of the hole forming strokes of the tool in one direction to be varied.

17. In a fastening inserting machine, means for feeding strips of fastening material into a position to be operated upon, means for forming fastenings from said strips, tools operative as awls to form holes in a work piece and as drivers to drive fastenings into said holes, means comprising a spring-actuated plunger for operating said tools, mechanism for rendering said plunger inoperative to prevent movement of the tools, and means operatively connected to said mechanism for stopping the feed of said strips of fastening material.

AUGUSTUS D. WILLHAUCK.
